UNITED STATES PATENT OFFICE

GEORGE ERNEST CREED, OF LONDON, ENGLAND, ASSIGNOR TO D. GESTETNER LIMITED,
OF LONDON, ENGLAND

DUPLICATING WITH THE AID OF STENCILS

Application filed December 18, 1929, Serial No. 415,107, and in Great Britain December 20, 1928.

This invention relates to duplicating with the aid of stencils.

As is well known stencil sheets, which are treated for the production of stencils for use in duplicating manuscript or typewritten matter, drawings and the like, consist of a sheet of stencilizable material provided with or secured to a strip of relatively strong paper or the like which is commonly described as a stencil heading. To the heading is also secured a backing sheet which after the sheet has been stencilized or converted into a stencil, is separated from the heading.

Hitherto it has been the usual practice to provide in the stencil heading a plurality of holes or slots, which may be of L-shape, adapted to engage pins provided on the stencil fastening means which is part of the duplicating machine.

Similarly porous sheets adapted to be arranged between the stencil and the inking means of the duplicating machine have been provided with headings of this character.

It has, moreover, been proposed to form a stencil heading with tabs or projections having holes or slots formed therein, the sides of the tabs or projections being designed to facilitate the appropriate location of the stencil heading relatively to the stencil fastening means which is part of the duplicating machine and to assist in the engagement of the holes in the stencil heading with pins or studs provided on the fastening means.

In the following description the expression "stencil heading" will be employed generally as denoting the heading of a stencil or stencil sheet and the heading of a porous sheet or other device adapted to be mounted on the duplicating machine with one of its faces in contact with one or other of the faces of the stencil.

One object of the present invention is to provide an improved stencil heading adapted to facilitate the securing of stencils, stencil sheets, porous sheets and the like in position on a duplicating machine.

A further object of the invention is to provide stencils, stencil sheets, porous sheets, or the like having improved heading whereby

they may be secured in position on a duplicating machine.

According to the invention the stencil heading is furnished with one or more tongues or flaps or equivalent elements, the free ends of which, when directed towards the stencil, stencil sheet or the like, by their displacement away from the body of the stencil heading are adapted to co-operate with stencil fastening means on the duplicating machine and thereby secure or assist in securing stencils, stencil sheets, or the like in position thereon.

Thus, for example, the tongues or flaps or equivalent elements may be arranged to be displaced relatively to the remaining portion of the stencil heading in such manner that the fore edge or fore edges thereof will bear against an abutment member forming part of the fastening means.

In accordance with the invention the stencil heading may comprise tongues or flaps which are directed to the stencil or the like or are adapted to be directed thereto which as the result of their displacement from a plane parallel with the plane of the body of the stencil heading are adapted to co-operate with the stencil fastening means on the duplicating machine to secure or assist in securing the stencils, stencil sheets or the like with which the stencil heading is associated in position thereon.

Thus, the tongues or flaps or equivalent elements may be provided on the stencil heading in such manner that when they are moved about their point of connection with the remaining portion of the stencil heading into a position in which they are inclined at an angle therewith, the fore edge or fore edges of the tongues or flaps will be adapted to bear against an abutment member forming part of the fastening means of the duplicating machine.

For example, in accordance with the invention, the stencil heading is provided with tongues, flaps or equivalent elements which are directed towards the stencil sheet or the like or are adapted to be directed towards the same so formed or arranged that by means on the stencil fastening means on the dupl

cating machine they will be displaced about their point of connection with the body of the stencil heading into a position in which they will co-operate with the said fastening means and thereby secure or assist in securing the stencil, stencil sheet or the like in position thereon.

The stencil heading in accordance with the invention may conveniently be provided with 10 tongues, flaps or equivalent elements adapted by members associated with the stencil fastening means on the duplicating machine extending from one face of the heading to beyond the opposite face thereof to be moved about their points of connection into an inclined position with respect to the adjacent portion 15 of the stencil heading.

Preferably the tongues, flaps or equivalent 20 elements are formed, as for instance by shaping them so that their sides are inclined, in order to co-operate with correspondingly formed portions of the stencil fastening means, which is part of the duplicating machine, in ensuring that the major axis of the 25 stencil sheet shall be at right angles to the axis of rotation of the inking means of the duplicating machine.

Conveniently also the edge of the stencil heading remote from the stencil sheet or the like is formed or provided with indentations 30 adapted to guide the stencil heading into position and to facilitate in co-operation with the stencil fastening means of the duplicating machine in centering or aligning the 35 stencil sheet or the like on the machine, when the stencil heading is moved in one direction as, for instance, in the initial operation of engaging it with the stencil fastening means while as above indicated the tongues, flaps 40 or equivalent elements may be so formed as to assist in centering or aligning the stencil sheet or the like when the stencil heading is moved in the reverse direction.

The indentations may be in staggered relation with the tongues or flaps or may be otherwise arranged and conveniently they and the 45 tongues or flaps are V-shaped.

To facilitate the insertion of a stencil sheet, provided with such indentations, in a 50 typewriter for the purpose of stencilizing, the stencil heading may be provided with a detachable portion, the free edge of which is straight and which when removed from the remaining portion of the stencil heading 55 leaves the edge left by its removal provided with indentations.

Normally in accordance with the invention the tongues or flaps are formed in the stencil heading by providing therein one or more 60 suitably shaped incisions so as to provide one or more portions of the material of the stencil heading adapted to be displaced relatively to the remainder or main portion thereof.

The invention will be described further in 65 detail and by way of example with reference

to the accompanying drawings, in which:—

Figure 1 is a fragmentary view in elevation of a stencil sheet showing the stencil heading, and

Figure 2 is a similar view of a porous sheet 70 having a heading or stencil fastening means in accordance with the invention.

Figure 3 is a view in elevation of the stencil fastening means which will normally be secured to or form part of the duplicating 75 machine;

Figure 4 is a corresponding view of a modified construction incorporating a silk carrier provided on each of its two opposite ends with rigid members as illustrated in front 80 and side elevations, respectively, in Figures 5 and 6;

Figure 7 is a sectional view on a larger scale of one construction of the said means, and

Figure 8 is a front elevation of a generally known type of duplicating machine provided with stencil fastening means as illustrated in Figures 3 to 6 or in Figure 7,

Figure 9 being a corresponding and elevation thereof, while

Figures 10 and 11 are, respectively, fragmentary views in elevation of an alternative form of stencil heading provided on a stencil sheet and a backing sheet, respectively.

Referring to Figure 1, 1 represents a portion of the backing sheet of the stencil sheet, 2 a stencil sheet attached thereto, 3 the stencil heading which forms a continuation of the backing sheet which will normally be a sheet of relatively stiff paper doubled over adjacent to one end to provide a reinforced and strengthened portion forming the stencil heading, 4 are tongues or flaps formed in the stencil heading by providing therein V-shaped incisions 5, the top edge of the stencil heading being cut back to form recesses 6 in the vicinity of the incisions to prevent this portion of the heading being distorted in consequence of the displacement of the tongues when the stencil sheet is placed on the stencil-duplicating machine. In addition, deeper recesses 7 are provided in the stencil heading, as illustrated in Figure 1, these recesses being provided in the construction illustrated to enable the stencil sheet to be mounted on the duplicating machine in association with a porous sheet as illustrated in Figure 2.

In Figure 2, 8 illustrates the backing sheet for the porous sheet 9, which may be a sheet of yoshino paper, the backing sheet being provided merely for the purpose of facilitating the handling of a material of the flimsy character of yoshino paper or other suitable highly porous material.

The backing sheet which is engaged with the porous sheet at one end constitutes the heading 10 adapted to be secured to the stencil fastening means of the duplicating machine and this heading is furnished with

tongues 11 by forming in the material of the heading V-shaped incisions 12. Adjacent to these incisions recesses 13 are provided in the stencil heading for the purpose explained in connection with Figure 1 and other deeper recesses 14 are provided in the stencil heading. These deeper recesses, as will be seen, are arranged so that, when a structure as illustrated in Figure 1 is superimposed on a structure as illustrated in Figure 2 with the edges of the sheets in alignment, they will not be in register with the deep recesses 7 in the stencil sheet but with the tongues therein, while the deep recesses 7 in the heading of the stencil sheet will be in register with the tongues 11 on the heading of the porous sheet, the purpose of this arrangement being to enable the tongues on the two sheets to be displaced independently of one another in a manner hereinafter to be described.

Referring to Figures 3, 4 and 7, which illustrate the stencil fastening means normally secured to or forming part of the duplicating machine, 15 is the lower member thereof which will be located adjacent to the inking means of the duplicating machine and which extends the whole width thereof and 16 is an upper member hinged to the lower member by the pin 17 and associated with a spring 18 adapted to constrain the free edges of the two members to approach one another, a tongue 19 being provided for moving the upper member relatively to the lower member in opposition to the spring when engaging a stencil or porous sheet with the fastening means.

The upper member 16 is by a pressing operation formed with recesses 20, the forward limits 21 of these recesses forming abutments for the tongues on the stencil heading and the heading of the porous sheet.

In the construction illustrated in Figure 7, on the lower member 15 of the stencil fastening means are provided a plurality of tongues 22 certain of which are arranged to displace the tongues on the stencil heading or the tongues in the heading of the porous sheet in the manner shown in this figure thereby causing the forward edge of the tongues 4 or 11, as the case may be, to bear against the forward limits 21 of the recesses in the upper member which form an abutment for the tongues.

In the construction illustrated in Figure 4 the elevations 23 are the equivalents of the elevations 22 in Figure 7 but instead of being formed on the lower member of the stencil fastening means they are formed in the rigid member 24 which is secured to one end of the silk carrier 25, see Figures 5 and 6, the other end of which is secured in the rigid member 26. The member 24 is provided also with projections 27 on its under face adapted to engage in corresponding holes 28 in the lower member of the stencil fastening means. In the stencil fastening means a recess 29 is

provided in the rear edge of the rigid member 24 and a pin 30 is provided in the lower member of the stencil fastening means. This pin is provided to prevent the stencil being inadvertently inserted upside down in the stencil fastening means. When so engaged in the stencil fastening means the elevations 23, as will be seen, will be in position to displace the tongues on the heading of the stencil sheet and on the heading of the porous sheet.

As shown in Figures 3 to 7, the stencil fastening means is secured as in known constructions to a length of flexible and ink-proof sheet material 31, commonly known as the protector, which in turn is connected to a strip of rigid material 32 which is provided with slides 33 engaged by pins 34 on the rigid member. These slides are located adjacent to the holes 35 designed to engage pins 36 on the flexible steel bands 37 provided in the construction of duplicating machine illustrated in Figures 8 and 9, the upturned ends 38 of the slides 33 being arranged to be engaged by loops 39 in the ends of the springs 40 secured to the rigid member 26 provided in one end of the silk carrier. In this way the silk carrier, with the rigid member 24 engaged by the stencil fastening means will be drawn tightly over the inking rollers and the protector 31 will also be drawn taut.

In Figures 8 and 9, 41 are the side members of the duplicating machine, 42 and 43 the inking cylinders and 44 the pressure roller adapted to press the paper on which the matter cut in the stencil is to be formed against the stencil.

The stencil heading may be varied in form and construction within relatively wide limits without exceeding the scope of the present invention and Figures 10 and 11 show one of several possible alternative constructions of heading falling within the scope of the invention.

In Figure 10, 48 indicates the backing sheet of a stencil sheet, 49 the main portion of the heading which is formed with recesses 50 leaving V-shaped elements between them, the extremities 51 of which when bent along the dotted lines 52 constituting tongues or flaps adapted to be displaced in a manner similar to the tongues 7 in the construction illustrated in Figure 1 by the elevations 22 or 23 on the stencil fastening means (see Figures 4 and 7), the slots 53 being provided to enable the said elevations to effect such displacement.

In Figure 11, 54 indicates the backing of the porous sheet, 55 the extremities of V-shaped elements forming part of the heading which when bent over along the dotted lines 56 will constitute tongues adapted to be displaced by elevations on the stencil fastening means entering the holes 57.

The invention is particularly concerned

with stencil sheets for use with the fastening means as described in the specification of the copending application for Letters Patent No. 415,106.

Having now described my invention, what I claim as new and desire to secure by Letters Patent is:—

1. A stencil heading whereby stencil sheets, porous sheets, and the like may be engaged with the stencil fastening means of a duplicating machine, comprising a body portion and tongues connected with said body portion adapted when directed towards the stencil sheet by their displacement from the plane of the body portion to co-operate with the stencil fastening means of a duplicating machine in securing the stencil sheet in position thereon.
2. A stencil heading whereby stencil sheets, porous sheets, and the like may be engaged with the stencil fastening means of a duplicating machine, comprising a body portion and tongue elements hingedly connected with the body portion adapted when directed towards the stencil sheet by their displacement from the plane of the body portion to co-operate with the stencil fastening means of a duplicating machine in securing the stencil sheet in position thereon.
3. A stencil heading whereby stencil sheets, porous sheets and the like may be engaged with the stencil fastening means of a duplicating machine, said stencil fastening means including an abutment member, comprising a body portion and tongues connected with said body portion adapted when directed towards the stencil sheet by their displacement away from the plane of the body portion to bear against the abutment member of the stencil fastening means.
4. A stencil heading whereby stencil sheets, porous sheets and the like may be engaged with the stencil fastening means of a duplicating machine, said stencil fastening means including an abutment member, comprising a body portion of a width corresponding with the width of the stencil sheet and tongue elements hingedly connected with the body portion adapted by their displacement from the plane of the same to engage against the abutment member of the stencil fastening means.
5. A stencil heading whereby stencil sheets, porous sheets and the like may be engaged with the stencil fastening means of a duplicating machine, comprising a body portion and tongue elements in hinged connection with said body portion having their fore edges directed away from the hinged connection and towards the body of the stencil sheet.
6. A stencil heading whereby stencil sheets, porous sheets and the like may be engaged with the stencil fastening means of a duplicating machine, comprising a body portion, tongue elements in hinged connection with said body portion having their fore edges

directed away from the hinged connection and towards the body of the stencil and incisions in the body of the heading adjacent to the tongue elements adapted to facilitate displacement of the tongue elements from the plane of the body portion.

7. A stencil heading whereby stencil sheets, porous sheets, and the like may be engaged with the stencil fastening means of a duplicating machine, comprising a body portion and incisions therein leaving tongue elements adapted to be displaced relatively to the body portion.

8. A stencil heading whereby stencil sheets, porous sheets, and the like may be engaged with the stencil fastening means of a duplicating machine, comprising a body portion, incisions therein forming open-ended loops leaving tongues movable relative to the body portion.

9. A stencil heading whereby stencil sheets, porous sheets, and the like may be engaged with the stencil fastening means of a duplicating machine, comprising a strip of sheet material adapted to extend substantially across the inking means of a rotary duplicating machine and parallel with the axis of rotation of the said inking means, and bifurcated incisions in said strip

10. A stencil sheet, a heading formed of tough sheet material secured to one edge thereof and incisions in the heading leaving tongue elements, the free extremities of which are directed towards the stencil sheet.

11. A stencil sheet, a heading formed of tough sheet material secured to one edge thereof and bifurcated incisions in the heading leaving tongue elements, the free extremities of which are directed towards the stencil sheet.

12. A stencil sheet a heading formed of tough sheet material secured to one edge thereof and V-shaped incisions in the heading leaving tongue elements, the free extremities of which are directed towards the stencil sheet.

13. A stencil heading of relatively tougher material than the body of the stencil sheet connected therewith adjacent to one end of the stencil heading and bifurcated incisions in the stencil heading, the free edges of which are directed towards the stencil sheet.

14. A combined stencil sheet comprising a sheet of stencilizable material, a backing sheet of relatively flexible but tough material arranged on one side of the stencil sheet, a connection between the sheet of stencilizable material and the backing sheet adjacent to one end thereof and bifurcated incisions in the material of the backing sheet leaving tongues, the fore edges of which are directed towards the main portion of the stencil sheet

15. A combined stencil sheet comprising a sheet of stencilizable material, a backing

sheet of relatively flexible but tough material arranged on one side of the stencil sheet, a connection between the sheet of stencilizable material and the backing sheet adjacent to one end thereof and V-shaped incisions in the material of the backing sheet leaving tongues, the fore edges of which are directed towards the main portion of the stencil sheet.

16. A combined stencil sheet comprising a sheet of stencilizable material, a backing sheet of relatively flexible but tough material arranged on one side of the stencil sheet, a connection between the sheet of stencilizable material and the backing sheet adjacent to one end thereof and V-shaped incisions and V-shaped recesses in the free edge of the stencil heading, the apices of the V-shaped recesses and incisions being at right angles 20 with the line of connection between the stencilizable material and the backing sheet.

17. A stencil sheet, a heading of tough sheet material secured adjacent to one edge thereof and tongues on the said heading 25 adapted by displacement to effect engagement of the stencil sheet with the stencil fastening means of a duplicating machine.

18. A stencil heading comprising tongue elements normally in the plane of the heading adapted to be inclined relatively to the 30 heading to engage the stencil fastening means of a duplicating machine.

19. A stencil sheet comprising a heading, and tongue elements normally in the plane 35 of the heading adapted to be inclined relatively to the heading to engage the stencil fastening means of a duplicating machine.

In testimony whereof I have signed my name to this specification.
